UNITED STATES PATENT OFFICE

2,515,925

ROTARY DISPLAY RACK

Robert F. Johnson, Wenatchee, Wash.

Application March 25, 1947, Serial No. 737,056

10 Claims. (Cl. 40—104)

1

An object of my invention is to provide a rotary display rack which is an improvement over my patent for a similar device issued May 4, 1926, No. 1,583,158. In the patent I show two pairs of rotary arms, each pair carrying a sheet-engaging roller for turning successive sheets so that each sheet in a group may be examined individually for a predetermined length of time before another sheet comes into view.

In my present device, I make use of novel means for causing the roller to be maintained in proper parallel arrangement with the plane of the front sheet during the movement of the sheet-engaging roller. The means performs an additional function of successively engaging with the bottom of each sheet and carry it forwardly and upwardly and over the top of the group of sheets and finally releases it so that the sheet will drop to the back of the group. The device can carry any number of sheets up to its full capacity. Adjustment is made to accommodate any number of sheets up to this full capacity.

Other objects and advantages will appear in the following specification, and the novel features of the device will be particularly pointed out in the appended claims.

Figure 1 is a perspective view of the entire device;

Figure 2 is a front elevation on an enlarged scale, a portion being broken away to show the motor drive;

Figure 3 is an end view of the rotating frame;

Figure 4 is an enlarged vertical section through the left hand bearing shown in Figure 2 that rotatably carries the sheet-turning frame;

Figure 5 is a top plan view of Figure 4;

Figure 6 is a perspective view of one of the arms that supports the removable sheets;

Figure 7 is a side elevation of Figure 2;

Figure 8 is an enlarged view of the sheet turning end of the rotating frame, portions being shown in section;

Figure 9 is a transverse section taken along the line IX—IX of Figure 8;

Figure 10 is an enlarged view of the star wheel;

Figure 11 is a horizontal section taken along the line XI—XI of Figure 8;

Figure 12 is a vertical section taken along the line XII—XII of Figure 2;

Figure 13 is a section taken along the line XIII—XIII of Figure 2 and shows the roller starter arm in various positions;

Figure 14 is a view similar to Figure 13, showing the star wheel and roller ready to be acted upon by the starter arm;

2

Figure 15 is an enlarged schematic view illustrating how the star wheel engages with a sheet of paper;

Figure 16 is a front elevation of a sheet illustrating how it is supported; and

Figure 17 is a top plan view of Figure 16 and illustrates how a sheet of paper may be removed from its supporting arms for closer inspection or to have another sheet substituted for it.

10 While I have shown only the preferred form of my invention, it should be understood that various changes or modifications may be made within the scope of the appended claims without departing from the spirit and scope of the invention.

In carrying out my invention, I provide a base indicated generally at A in Figure 1 and this base supports a frame indicated generally at B. The frame is shown on a larger scale in Figure 2 and comprises side members 1 and 2 extending upwardly from a lower housing indicated at C. Within the housing a motor D is mounted. Again referring to Figure 1, I show a metal frame E extending above the frame B and supporting a plate 3 that may contain any desired information, such as an advertisement.

Within the sides 1 and 2 of the frame B I rotatably mount a page or sheet turning frame indicated generally at F. The frame F has a pair of arms 4 and 5 that project radially from discs 6 and 14, respectively. The disc 6 is shown in enlarged section in Figure 4 and is rotatably mounted on a stub shaft 7, the latter being secured to the frame side 1 by a base portion 8 and screws or other suitable fastening means 9. A pulley 10 is rotatably mounted on the stub shaft and is keyed to the disc 6 at 11. Figure 2 illustrates how a belt 12 connects the pulley 10 to a pulley 12 that is mounted in the housing C. The latter pulley is connected to the motor D through suitable gear reduction mechanism, not shown.

The arm 5 is connected to the disc 14 that is similar to the disc 6 and the disc 14 is rotatably mounted on a stub shaft 15 which is carried by the frame side 2. Each arm 4 and 5 has an enlarged arcuate end shown at 16 in Figure 8. Since each enlarged end is the same in construction, a description of one will suffice for both. The arcuate end 16 has a slot 17 therein and the slots of the two ends receive a paper sheet engaging roller shaft 18, see Figure 3. The shaft 18 has a roller 19 rigidly mounted at each end thereof and each roller has conically-shaped flanges 19a as shown in Figures 9 and 11. The arrangement is such that the rollers 19 are free to roll along

the slots 17 provided in the enlarged ends 16 of the arms and the flanges guide the rollers in their movement.

It is necessary that the two rollers 19 be synchronized in their rotation along the slots so that the axis of the roller shaft 18 will remain parallel to the rotative axis of the frame F at all times. To accomplish this I secure a cable 20 to the arcuate end 16 at 21, see Figure 8, and the cord extends through a bore 22. The cable 20 has its other end wrapped around the roller 19 with a few turns, see Figure 11, and then the end is secured to the roller. A second cable 23 has one end secured to the same roller and is wrapped around this roller for a few turns in the same direction as the other cable 20, and then the free end of the cable 23 is secured to a coil spring 24, see Figure 8. The spring is mounted in a bore 25 and has its other end attached to the arm portion 16 at 26. When the arm is swung into a position for causing the slot 17 to be inclined upwardly, the roller shaft 18 will move by gravity and its rotative movement will be controlled by the cables 20 and 23, one cable winding up on the roller 19 while the other unwinds, this depending in which direction the shaft moves. The arrangement is such that the roller shaft can move throughout the entire length of the slots 17.

At the center of the shaft 18, and between the rollers 19, I mount a star wheel indicated generally at G, see Figure 3. An enlargement of this wheel is shown in Figure 10 and it will be seen that the wheel has a plurality of wire-engaging teeth 27 thereon. I show four teeth spaced equal distances apart and each tooth has a recess 27a associated therewith and large enough to receive a wire 28 that is carried at the lower end of a sheet of paper indicated generally at H.

The particular size of the paper used can be varied up to the limits of the machine and I show in Figure 16 the sheet H as having a wire 29 extending across its top and paralleling the bottom wire 28. The top wire 29 projects beyond the sides of the sheet and the ends of the wire are received in slots 30 formed in the heads 31 of a pair of stationary upright arms 32, see one of the heads in Figure 6. Referring to Figures 2 and 4, it will be seen that the arms 32 extend through openings in the stationary stub shafts 7 and 15 and are held in adjusted position by set screws 33, see Figure 5. The heads 31 are arranged so that both slots 30 will be at the same height above the pivotal axis of the frame F. Figure 12 indicates how the lower edge of the slot 30 is inclined so that the ends of the top wires 29 will gravitate toward the end 30a of the slot.

The star wheel G will be in a position to have one of its teeth 27 catch the wire 28 on the foremost page H, which will be the right hand page when looking at Figure 12. As already stated, the roller shaft 18 will move by gravity when the ends 16 of the arms 4 and 5 start to swing forwardly and upwardly so as to incline the slots. The cables 20 and 23 will control the rotation of the shaft and the cables 23 will cause it to rotate in a counterclockwise direction when looking at Figure 10. Figure 15 illustrates how the tooth 27 engages with a bottom wire 28 of the foremost sheet or page and causes this wire to be received in the associate recess 27a.

It is necessary that the shaft 18 be started in its rotative and rearward movement toward the first page H after the end 16 of each arm has moved a predetermined distance beyond this

front page. Figure 14 illustrates the roller shaft 18 and star wheel in dotted position at the forward end of the slot 17 and received in the slot depression 42, while Figure 2 shows the right-hand arm end 16 carrying a pin 34 that engages with a starter arm 35, the latter being pivoted at 36 to the inner surface of the frame side 2. A coil spring 37, see Figure 13, normally holds the arm 35 against a rubber bumper or stop 38, also carried by the inner surface of the side frame 2. Figure 13 indicates how the pin 34 carried by the arcuate arm end 16 swings the starter arm 35 in a counterclockwise direction until the free end of this arm is released from the pin. At this point the spring 37 has been tensioned as shown in Figure 14 and will swing the arm clockwise and cause it to contact with the portion of the roller shaft 18 extending beyond the right-hand end of the frame F, shown in Figure 2. The shaft will rotate and move along the slot and the star wheel will be rotated counterclockwise by the shaft to engage with the wire 28 as shown in Figure 15.

As the roller shaft carrying arms 4 and 5 continue to rotate in a counterclockwise direction when looking at Figure 7, the weight of the roller shaft 18 plus the pull of the cables 23 will urge one of the teeth 27 to engage with the wire 28. Furthermore, Figure 10 shows how the portion of the paper H disposed adjacent to the star wheel is held taut by the tooth so as to aid in maintaining the wire in the recess 27a. The forward and upward swing of the arms 5 and 6 will therefore lift the lower free end of the paper H as shown in Figure 7 and a new sheet will thus be uncovered and viewable by a person standing or sitting in front of the machine.

The continued tendency of the star wheel to rotate counterclockwise will keep its tooth engaged with the wire 28 until the sheet or page reaches the top position shown in dotted lines in Figure 7. When the arm ends 16 pass beyond this top position, as shown in Figure 12, the slots 17 will be inclined downward and the roller shaft 18 will tend to return in its movement along the lengths of the slots 17. The cables will rotate the shaft in an opposite or clockwise direction and will free the star wheel from the wire 28 with the result that the end of the sheet will be freed. The freeing takes place after the top wire 29 of the moved sheet is transferred from a position in front of the group of wires to the back of the same group. The turned sheet will now drop in back of the group of sheets as clearly shown in Figure 12.

The effective length of each slot 30 is controlled by means of an adjustable U-shaped frame J, see Figure 6. This frame has a pair of inclined edges 39 against which the ends of the wire 29 contact after the page has been removed from the front of the group of pages to the back. The inclined edges 39 guide the wire 29 down to the lower side of the slot 30 and this lower side has enough angle to cause the wires to move forwardly as the forward pages are turned to the back of the group. An adjusting screw 40 is carried by each head 31 and is threaded into a sleeve 41 carried by each frame J so that the frames can be adjusted along the lengths of the slots to uncover as much of them as desired.

Should the wire 28 become caught in the star wheel due to the over-riding of the wheel by the freed end of the paper at the moment of release, the springs 24 will yield and permit movement 75 of the cables 23, which in turn will permit the

roller shaft 18 to move a sufficient distance to disengage the star wheel tooth from the wire. Figure 13 shows the forward end of the slot 17 provided with a depression 42 for receiving the roller shaft 18. When the shaft is in this depression or recess of each slot, it will place the star wheel far enough away from the center of rotation of the paper turning frame F and far enough away from the slots 30 so as to permit the wheel to pass under the lower edges of the group of pages without engaging them or the wires 28. The wheel is brought into proximity with the pages when it leaves the depressions 42 and moves toward the front page as shown in Figures 14 and 15.

It is possible to provide two arms with their enlarged arcuate ends 16 and associate roller shaft 18 and star wheel 19 so that two pages will be turned for each rotation of the frame. In the present form, I have shown only one pair of arms and these are counter-balanced by arms 43. The counter-balancing of the arms 43 permits the motor to rotate the arms 4 and 5 freely without needing much power.

If it is desired to remove a page from the machine for closer examination, this can be done by flexing the top wire 29 as shown in Figure 17 for freeing its ends from the slots 30. It is possible to add the sheet to the group after it has been examined or to substitute a new sheet. The machine is continuous in operation so long as the motor is connected to a source of current.

I claim:

1. A rotary display rack comprising a pair of spaced supports, each having an inclined slot; a plurality of pages, each having a supporting member whose ends are slidably received in the slots and movable by gravity toward the lower ends of the slots, the pages being suspended from the members; a pair of spaced and parallel arms disposed on opposite sides of the suspended pages, means for rotating the arms in unison in planes at right angles to the planes of the pages, the outer end of each arm having a slot that moves adjacent to the lower ends of the pages during a portion of the arm travel, a shaft having rollers movable along the arm slots by gravity; positive means for rotating the rollers as they move along their slots; a star wheel carried by the shaft, and having teeth, the lower ends of the pages having wires adapted to be engaged by the teeth; the arm slots being inclined upwardly as the outer arm ends swing by the lower ends of the pages, whereby the rollers and shaft will be rotated for causing a tooth of the star wheel to engage with the page wire nearest thereto and to lift and turn the page as the arms travel through their circle.

2. A rotary display rack comprising a pair of spaced supports, each having an inclined slot; a plurality of pages, each having a supporting member whose ends are slidably received in the slots and movable by gravity toward the lower ends of the slots, the pages being suspended from the members; a pair of spaced and parallel arms disposed on opposite sides of the suspended pages, means for rotating the arms in unison in planes at right angles to the planes of the pages, the outer end of each arm having a slot that moves adjacent to the lower ends of the pages during a portion of the arm travel, a shaft having rollers movable along the arm slots by gravity; positive means for rotating the rollers as they move along their slots; a star wheel carried by the shaft, and having teeth, the lower ends of the pages having

wires adapted to be engaged by the teeth; the arm slots being inclined upwardly as the outer arm ends swing by the lower ends of the pages, whereby the rollers and shaft will be rotated for causing a tooth of the star wheel to engage with the page wire nearest thereto and to lift and turn the page as the arms travel through their circle, and adjustable brackets for the supports for limiting the effective lengths of the support slots for holding the desired number of page supporting members, the brackets guiding the supporting member of the turned page to the opposite end of the supporting slots formerly occupied just prior to the page being turned.

3. In a rotary display rack; inclined page supporting means; a plurality of pages, each having supporting members whose ends are supported by said means and slide by gravity in one direction; a rotary frame having its axis of rotation disposed below the page supporting members and having means associated with the end thereof for successively engaging with the lower ends of the pages for turning them for display purposes and causing the page supporting members to move from one end of the page supporting means to the opposite end, the rotary frame having sufficient length from the axis of rotation to the page engaging means for carrying said means over the top of the page supporting means so that the lower end of each page will be carried across the tops of all other pages on the page supporting means.

4. In a rotary display rack; inclined page supporting means; a plurality of pages, each having supporting members whose ends are supported by said means and slide by gravity in one direction; a rotary frame having its axis of rotation disposed below the page supporting members and having means associated with the end thereof for successively engaging with the lower ends of the leaves for turning them for display purposes and causing the page supporting members to move from one end of the page supporting means to the opposite end, said page engaging means including means for disengaging the frame from the page after the turning movement has been effected.

5. In a rotary display rack, a page supported at its upper edge, mechanical means for turning the page about its top edge and comprising a frame pivoted to straddle the page and having guide slots therein, means for rotating the frame, a shaft, rollers supporting the shaft and movably receivable in the slots, means carried by the shaft for engaging with the lower edge of the page as the slots are carried past the same by the rotating frame and causing the said edge to follow its course, and positive means for rotating the rollers as they move along the slots for causing the page engaging means to grip the page.

6. In a rotary display rack, a page supported at its upper edge, mechanical means for turning the page about its top edge and comprising a frame pivoted to straddle the page and having guide slots therein, means for rotating the frame, a shaft, rollers supporting the shaft and movably receivable in the slots, means carried by the shaft for engaging with the lower edge of the page as the slots are carried past the same by the rotating frame and causing the said edge to follow its course, and positive means for rotating the rollers as they move along the slots for causing the page engaging means to grip the page, said last-named means including means for freeing the page after it has been turned.

7. In a rotary display rack, a page supported at its top edge, mechanical means for turning the page about its top edge and comprising a frame pivoted to straddle the page and having a pair of slots therein, means for rotating the frame, a shaft, rollers secured to the shaft and riding in the slots, a toothed wheel rotated by the shaft and having teeth falling into engagement with the lower edge of the page as the slots pass the same, and causing the edge to follow the course of the slots, and positive means for rotating the rollers when the slots are inclined from the horizontal during the rotation of the frame, whereby a better grip of the tooth on the page is effected.

8. In a rotary display rack, a page supported at its top edge, mechanical means for turning the page about its top edge and comprising a frame pivoted to straddle the page and having a pair of slots therein, means for rotating the frame, a shaft, rollers secured to the shaft and riding in the slots, a toothed wheel rotated by the shaft and having teeth falling into engagement with the lower edge of the page as the slots pass the same, and causing the edge to follow the course of the slots, and positive means for rotating the rollers when the slots are inclined from the horizontal during the rotation of the frame, whereby a better grip of the tooth on the page is effected, said last-named means reversing the rotation of the wheel to free it from the page after the page has been advanced sufficiently to drop by its own weight.

9. In a rotary display rack, a plurality of pages supported at their upper edges, mechanical means for turning the pages successively about their top edges and comprising a frame pivoted to straddle the group of pages and having a pair of slots therein, means for rotating the frame, a shaft, rollers secured to the shaft and riding in

the slots, a toothed wheel rotated by the shaft and having teeth adapted to engage with the lower edge of the page nearest the wheel as the slots pass the same, an arm pivoted and disposed adjacent to the path taken by the slots as they pass the lower edges of the pages, a pin carried by the frame for swinging the arm away from the first page of the group as the frame passes thereby and for freeing the arm after it has been swung a predetermined distance, the shaft having an end extending into the swinging path of the arm against the shaft when the pin frees the arm, whereby the shaft is positively started in its travel toward the nearest page

10. In a rotary display rack, a page supported at its upper edge, mechanical means for turning the page about its top edge and comprising a frame pivoted to straddle the page and having guide slots therein, means for rotating the frame, a shaft, rollers supporting the shaft and moveably receivable in the slots, a wire carried by the lower edge of the page, the page having a cut-away portion for exposing a part of the wire, a toothed wheel carried by the shaft for engaging with the wire as the slots are carried past the page by the frame, said tooth also pressing against the adjacent portion of the page to aid in keeping the wire in engagement with the tooth.
